A. B. N. MOSS

STATUE

Filed Aug. 10, 1928

FIG. 4

FIG. 3

FIG. 2

FIG. 1

Inventor:
Arlene B. N. Moss,
by Ripley & Kingsland,
Her Attorneys.

UNITED STATES PATENT OFFICE.

ARLINE B. N. MOSS, OF ST. LOUIS, MISSOURI, ASSIGNOR TO THE NATIONAL SOCIETY
OF THE DAUGHTERS OF THE AMERICAN REVOLUTION, OF WASHINGTON, DISTRICT OF COLUMBIA.

DESIGN FOR A STATUE.

Application filed August 10, 1928. Serial No. 27,772 Term of patent 14 years.

To all whom it may concern:

Be it known that I, ARLINE B. N. Moss, a citizen of the United States, residing at the city of St. Louis and State of Missouri, have invented a new, original, and ornamental Design for Statue, substantially as shown in the accompanying drawing, in which—

Fig. 1 is a side-front elevation of the statue.

Fig. 2 is a right side elevation.

Fig. 3 is a left side elevation.

Fig. 4 is a rear elevation.

I claim:

The ornamental design for a statue, substantially as shown.

ARLINE B. N. MOSS.
